[57] CLAIM

The ornamental design for a binocular, as shown and described.

DESCRIPTION

FIG. 1 is a bottom perspective view of the binocular showing our new design, with both ocular cylinders shown retracted;

FIG. 2 is a front elevational view thereof;

FIG. 3 is a top plan view thereof, with both ocular cylinders shown extended;

FIG. 4 is a top plan view thereof, with the binocular shown in the closed position and both ocular cylinders retracted;

FIG. 5 is a rear view thereof;

FIG. 6 is a left side elevational view thereof.
